CLAIM

An ornamental design for a rotary latch, as shown and described.

DESCRIPTION

FIG. 1 is a parallel perspective view of a rotary latch embodying our new design;

FIG. 2 is a top plan view thereof;

FIG. 3 is a bottom plan view thereof;

FIG. 4 is a front elevation view thereof;

FIG. 5 is a rear elevation view thereof; and,

FIG. 6 is a left side elevation view thereof, the right side being a mirror image of the left.
